UNITED STATES PATENT OFFICE.

LAWRENCE E. JOHNSTON, OF ST. LOUIS, MISSOURI.

VALVE.

Application filed December 8, 1922. Serial No. 605,686.

To all whom it may concern:

Be it known that I, LAWRENCE E. JOHNSTON, a citizen of the United States, residing at St. Louis, in the State of Missouri, 5 have invented new and useful Improvements in Valves, of which the following is a specification.

This invention relates to internal combustion engines, and more particularly to 10 the valves therefor.

The invention has for its object, the provision of a rotary valve, and contemplates a construction which assures a leak proof valve, and one which prevents carbon from 15 accumulating around the valve and its seat, thereby maintaining the efficiency of the motor, and also eliminating the trouble usually experienced with dirty valves.

The nature and advantages of the invention will be better understood when the following detailed description is read in connection with the accompanying drawings, the invention residing in the construction, combination and arrangement of parts as 25 claimed.

In the drawings forming part of this application, like numerals of reference indicate similar parts in the several views, and wherein:

30 Figure 1 is a side elevation of engine head equipped with the valve mechanism.

Figure 2 is a longitudinally sectional view therethrough.

Figure 3 is a transverse sectional view.

35 Figure 4 is a detail view of one of the valves.

Figure 5 is a detail view of one of the adjusting yokes.

40 Figure 6 is a sectional view taken on the line 6—6 of Figure 1, looking in the direction of the arrows.

Referring to the drawings in detail, 10 indicates the head of an internal combustion engine, which is provided with an inlet port 10 and an exhaust port 11 for each cylinder, and further provided with a vertical bore 13 which communicates with said ports as illustrated. The bore 13 is tapered toward its lower end, and adjacent this end 45 there is a tapered shoulder 14 upon which the adjacent end of a cylindrical valve 15 reposes. The valve 15 is of course correspondingly tapered to fit snugly within the bore 13, and the valve is provided with an 55 opening 16 which is adapted to alternately communicate with the inlet and outlet ports

above mentioned. These ports together with the openings 16 are of such size that the charge of fuel can be quickly admitted into the combustion chamber, and the exhaust gases permitted to escape in quick order. The valve is provided with an annular flange 17 which surrounds the upper end of the valve and reposes upon the head 10 being arranged within a large annular 60 recess 18 formed in the head, so that the flange 17 lies substantially flush with the upper surface of the head. It will be noted that the valve is hollow, and that the interior of the valve communicates with the 65 combustion chamber of the adjacent cylinder of the engine, the construction which permits the size of the combustion chamber to be regulated for high compression 70 motors. The valve is provided with spiral 75 grooves 19 to assist in lubricating the valve and the wall of the valve seats in a manner to be hereinafter described.

The flange of each valve is provided with an annular series of teeth 20, and meshing 80 with these teeth is a bevel gear 21 which is carried by an overhead shaft 22, the latter being journaled in a housing construction indicated generally at A. This shaft 22 may be rotated in any suitable manner, and 85 it is of course understood that there is one of the bevel gears for each of said valves. The valves for the respective cylinders are so arranged, and the shaft operated at a speed for a proper timing of the valves as 90 will be appreciated.

The housing above referred to is made up of a plurality of substantially dome shaped portions 25, there being one of these portions arranged above each valve and 95 provided with a gasket 26 which is positioned in the recesses formed in the head of the valve around the flange 16 thereof. The shaft operates in a lubricant which is adapted to be contained in the housing 100 which also lubricates the driving connection between the shaft and the valves. The head 10 is provided with a vertical bore 26 which is arranged in juxtaposition to each bore 13, and this bore 26 opens into 105 the bore 13 at points above and below the opening in the valve. Consequently, the oil from the housing enters the bore 26 which also opens at the top of the head, and passes from the bore 26 to the spiral 110 passages of the valves, which carries the lubricant upwardly in a manner to effec-

tively lubricate both the valve and its seat.

Arranged in each dome shaped portion of the housing is a two part yoke, the respective parts being indicated at 28 and connected together by suitable fastening elements 29. The shaft 22 passes through all of these yokes, and each yoke is mounted for sliding adjustment within its particular portion of the housing, for the purpose to be presently set forth. The lower part of each yoke is provided with a spherical portion 29 which is received within a socket or recess 30 formed in the upper end of the valve, while the upper part of the yoke is formed with semi-spherical depressions indicated at 31. Each dome shaped portion is provided with a central opening to receive a threaded adjusting element 32 which terminates to provide a ball like extremity 32 received by the depression 31 of the adjacent yoke, so that by tightening this element 32 the yoke is depressed against the valve to hold the latter effectively seated, and thereby render the valve leak proof. Each yoke is provided with lugs 34 which project from the end thereof, and are received within the opposite grooves 35 which guide the yokes in their adjustments. The construction and operation of the valve mechanism is such, that carbon is not allowed to accumulate around the valve or the valve seat, and in addition to eliminating trouble usually experienced with dirty valves the motor will always operate with a high degree of efficiency.

While it is believed that from the foregoing description, the nature and advantages of the invention will be readily apparent, I desire to have it understood that I do not limit myself to what is herein shown and described and that such changes may be resorted to when desired as fall within the scope of what is claimed.

Having thus described the invention, I claim:

1. In an internal combustion engine, a head having inlet and exhaust ports, and a communicating bore arranged at a right angle thereto, a hollow valve arranged in said bore and having an opening adapted to alternately communicate with said ports, an annular flange on the upper end of said bore and reposing upon said head, said flange being formed with a central depression, a housing including spaced dome shaped portions arranged above said valve, a shaft journaled in the housing, means for rotating said valve incident to the rotation of said shaft, an adjustable yoke arranged within each portion of the housing and receiving said shaft, each yoke including a spherical portion seated in the recess of said valve, and means for adjusting said yoke whereby the latter holds the valve effectively seated.

2. In an internal combustion engine, a head having inlet and exhaust ports, and a communicating bore arranged at a right angle thereto, a hollow valve arranged in said bore and having an opening adapted to alternately communicate with said ports, a flange arranged at one end of the valve and reposing on said head, teeth on said flange, a housing including spaced portions arranged above each valve, a shaft journaled in said housing, a gear carried by the shaft for each valve and arranged in one end of said portions of the housing, said gear meshing with the teeth of the flange whereby the valve is rotated incident to the rotation of the shaft, a hole slideable on each portion of the housing, and bearing against the flange of said valve, and an adjustable element projecting from the top of said housing and connected with said yoke, whereby the latter can be adjusted to effectively hold the valve seated.

In testimony whereof I affix my signature.
LAWRENCE E. JOHNSTON.
